INVENTOR

JOHN W. MILLER
BY *John W. Miller*

ATTORNEYS

UNITED STATES PATENT OFFICE.

JOHN W. MILLER, OF WAUKEGAN, ILLINOIS.

SMOKING APPLIANCE.

Application filed January 27, 1921. Serial No. 440,870.

To all whom it may concern:

Be it known that I, JOHN W. MILLER, a citizen of the United States, and a resident of Waukegan, in the county of Lake and State of Illinois, have invented a new and Improved Smoking Appliance, of which the following is a full, clear, and exact description.

This invention relates to improvements in smoking appliances, particularly cigar and cigarette holders, an object of the invention being to provide a cigar or cigarette holder which will be capable of radial adjustment to firmly grip the end of a cigar or cigarette.

15 A further object is to provide a holder which will be simple and practical in construction, efficient and durable in use, and neat and attractive in appearance, and to provide an improved clamping or adjusting mechanism associated therewith which will not materially increase the cost of the holder.

25 With these and other objects in view, the invention consists in certain novel features of construction and combinations and arrangements of parts, as will be more fully hereinafter described and pointed out in the claims.

In the accompanying drawings:

30 Figure 1 is a perspective view of my improved device.

Figure 2 is a view in longitudinal section therethrough.

Figure 3 is a view in transverse section on the line 3—3 of Figure 2.

35 Referring in detail to the drawings, 1 represents the stem or mouth piece of a cigar or cigarette holder. The mouth piece is formed with the usual longitudinal smoke passage 2 which communicates with the cigar or cigarette receiving recess 3 in the enlarged end or barrel 4 of the holder.

40 Around the mouth of the holder an external flange 5 is provided and an external annular flange 6 around the intermediate portion of the holder is preferably made integral with the holder.

45 The recessed or socket end of the holder is formed with a pair of longitudinal diametrically opposed slots such as 7.

50 8 represents a split sleeve preferably in the form of a metal clip, which encircles the holder and which is confined between the

flanges 5 and 6. The adjacent ends of the split sleeve 8 are in the form of upstanding parallel flanges 9. A pin 10 connects the flanges, and on this pin a cam 11 is mounted to rotate. An operating lever 12 is preferably integral with the cam.

In operation, the end of a cigar or cigarette is inserted in the recess or socket 3. The lever 12 is then swung, causing the cam 11 to engage the walls of the barrel 4. The slits 7 permit a clamping action of the walls of the recess 3 on the end of the cigar or cigarette as the case may be, and serve to tightly grip the end of the same within the holder.

It will be apparent that the design of the holder might be considerably varied, that other means might be resorted to for compressing the slit barrel, and that various slight changes and alterations might be made in the general form and arrangement of the parts described without departing from the invention, and hence I do not limit myself to the precise details set forth but consider myself at liberty to make such changes and alterations as fairly fall within the spirit and scope of the appended claims.

It might be said in the conclusion that the lever 12 not only serves as a cam actuating member, but is also utilized as a dip to retain the holder in place in a pocket when not in use.

I claim:

1. A holder of the character described, having a socket in one end, a split sleeve around the holder, and means pivoted between the adjacent edges of the split sleeve to regulate the size of the socket.

2. A holder of the character described, having a socket at one end, the walls of said socket being slit longitudinally, a split sleeve around the holder, the adjacent edges of said sleeve comprising upstanding parallel flanges spaced apart, a pin connecting the flanges, a cam pivoted on the pin, and a lever integral with the cam.

3. A holder of the character described, having a contractile socket at one end, a split sleeve encircling the holder, a lever pivoted between the adjacent edges of the split sleeve and engageable with the holder to contract the socket.

JOHN W. MILLER.
